US0D1027449S

(12) United States Design Patent (10) Patent No.: US D1,027,449 S
(45) Date of Patent: * May 21, 2024

(54) BASKET

(71) Applicant: AT SYSTECH SDN BHD, Selangor (MY)

(72) Inventor: Kelvin Weng Liang Tan, Rawang (MY)

(73) Assignee: AT SYSTECH SDN BHD, Rawang (MY)

() Term: 15 Years

(21) Appl. No.: 29/811,214

(22) Filed: Oct. 12, 2021

(30) Foreign Application Priority Data

May 17, 2021 (MY) 21-E0554-0101

(51) LOC (14) Cl. 09-04

(52) U.S. Cl.
